UNITED STATES PATENT OFFICE.

EDWIN JOSEPH MORGAN, OF NORWICH, ENGLAND.

SASH-FASTENER.

SPECIFICATION forming part of Letters Patent No. 608,786, dated August 9, 1898.

Application filed October 2, 1897. Serial No. 653,857. (No model.)

To all whom it may concern:

Be it known that I, EDWIN JOSEPH MORGAN, gentleman, a subject of Her Majesty the Queen of Great Britain and Ireland, residing 5 at 76 St. Giles street, Norwich, in the county of Norfolk, England, have invented certain Improvements in or Relating to Window-Sash Fasteners, of which the following is a specification.

10 The object of the present invention is to provide an efficient burglar-proof sash-fastener of simple and economical construction.

15 My invention consists in the structure and arrangement of parts hereinafter particularly claimed.

In the drawings, Figure 1 is a side view, Fig. 2 a plan, and Figs. 3 and 4 details, of the invention.

20 To the meeting-bar A is secured the bracket a, in which moves the short rock-shaft b*, capable of receiving longitudinal as well as partial rotary motion. To one end of this rock-shaft b* is secured the locking-hook c*, adapted to pass through the socket-piece or staple d*, secured to the bar B, and to the other end 25 is secured the lever-handle e.

25 The rock-shaft b* is partly cut away at that end adjacent to the locking-hook c*, as shown in Figs. 1 and 2, to enable the rock-shaft to 30 be moved forward even when the meeting-bars are not quite level. When the lever-handle e is turned, the flat portion of the rock-shaft b* acts against the under face of the 35 socket-piece or staple d* and raises the meeting-bar B of the upper sash or depresses the meeting-bar A of the lower sash, as the case may be, thus closing the window completely.

The socket-piece or staple d* is beveled off on the top at d² and the locking-hook c* is beveled off as shown in Fig. 2. Thus when 40 the lever-handle e is turned down the two inclines acting against each other cause the meeting-bars to be in close contact.

45 It will be understood that the lever e and rock-shaft b* are moved into the position shown in dotted lines in Figs. 1 and 2 when it is desired to open the window, thus removing the end of the rock-shaft b* and the locking-hook c* from the socket-piece or staple d*, and in this position the locking-hook c* 50 can readily pass the lateral sash-bars.

What I claim, and desire to secure by Letters Patent of the United States, is—

55 In combination, the staple having an inclined edge and secured to one sash, the rock-shaft, the bearing therefor, said rock-shaft being adapted to pass through the said bearing longitudinally and independent of its rotation, the hook on the said rock-shaft adapted to pass through the staple and having an inclined end to work against the staple whereby the sashes will be drawn together vertically, the said shaft having also a cut-away or cam portion for bearing upon the under side of the 60 staple to draw the sashes together vertically. 65

In testimony whereof I have signed my name to this specification, in the presence of two subscribing witnesses, this 17th day of September, 1897.

EDWIN JOSEPH MORGAN.
